UNITED STATES PATENT OFFICE.

JOSEPH KEPPLER, OF NEW YORK, N. Y., ASSIGNOR TO BENJAMIN T. B. HYDE,
OF NEW YORK, N. Y., TRADING AS HYDE EXPLORING EXPEDITION.

DESIGN FOR A PANEL OR UPRIGHT FOR FURNITURE.

SPECIFICATION forming part of Design No. 36,253, dated March 24, 1903.

Application filed February 24, 1903. Serial No. 144,925. Term of patent 7 years.

To all whom it may concern:

Be it known that I, JOSEPH KEPPLER, a citizen of the United States, residing at the city of New York, in the county and State of New York, have invented and produced a new, original, and ornamental Design for Panels or Uprights for Furniture, of which the following is a specification, reference being had to the accompanying drawing, forming part hereof, and in which a panel or upright showing my design is illustrated by a perspective view.

As illustrated in the drawing, the leading or material feature of my design consists in the shape or configuration of the panel or upright, combined with the surface ornamentation thereof.

As illustrated, the panel or upright has a main body *a* of rectangular outline surmounted by zigzag ornamental projections *b*, having zigzag surface ornamentations *b'* to represent in Indian mythology successive terraces of clouds. The body *a* is also ornamented on its surface with symbolic ornamentations. Below the main body *a* projects the curved base *d*, which in outline or configura-

tion represents conventionally a porcupine according to Indian mythology. This base *d* has surface ornamentations *d'*, *d''*, and *d'''*, accentuating the representation of the porcupine by ornamenting the outline with conventional representations of quills and other appendages of the porcupine.

The design when viewed in front elevation has the appearance of a mythological porcupine of conventional form supporting a rectangular panel, which in turn is capped by cloud terraces conventionally represented according to Indian mythology.

Having thus described my invention, what I claim as new, and desire to secure by Letters Patent, is—

The ornamental design for a panel or upright for furniture, substantially as herein shown and described.

In testimony whereof I have hereunto set my signature in the presence of two subscribing witnesses.

JOS. KEPPLER.
